L. B. LIEBERMAN ET AL

SOAP HOLDER

Filed March 20, 1926

Inventors

Louis B. Lieberman,
Albert M. Dunn,

By Attorney

UNITED STATES PATENT OFFICE.

LOUIS B. LIEBERMAN AND ALBERT M. DUNN, OF BALTIMORE, MARYLAND, ASSIGNORS
OF ONE-THIRD TO NICOLA ROSSINI, OF BALTIMORE, MARYLAND.

DESIGN FOR A SOAP HOLDER.

Application filed March 20, 1926. Serial No. 17,001. Term of patent 3½ years.

To all whom it may concern:

Be it known that we, LOUIS B. LIEBERMAN and ALBERT M. DUNN, citizens of the United States of America, residing at Baltimore, in the city of Baltimore and State of Maryland, have invented a new, original, and ornamental Design for Soap Holders, of which the following is a specification, reference being had to the accompanying drawing, forming a part thereof.

The figure is a perspective view of the soap holder showing our new design.

We claim:

The ornamental design for a soap holder as shown.

LOUIS B. LIEBERMAN.
ALBERT M. DUNN.
